UNITED STATES PATENT OFFICE

JOHN POLACHEK, OF NEW YORK, AND JULIUS A. JEPSEN AND EDMUND PEREMI, OF ELMHURST, NEW YORK, ASSIGNORS TO GENERAL BRONZE CORPORATION, OF LONG ISLAND CITY, NEW YORK, A CORPORATION OF NEW YORK

ANTIRATTLING SPRING FOR WINDOW SASHES

Application filed May 24, 1929. Serial No. 365,610.

This invention relates to improvements in windows and more particularly to devices or means for providing air and dust-proof joints between the fixed frames and their associate parts and the movable sashes, and further to prevent undue lateral play of the sashes in their guideways, thus eliminating rattling.

The present invention is particularly adapted for effective use in connection with windows having metallic frames and sashes constructed as shown and described in patent granted to us on July 19, 1927, No. 1,636,241, "window", wherein the sash guides members are formed with grooves, but, of course, the invention may be applied to window frames not provided with these grooves, if sufficient space is provided for the installation thereof.

This device is also intended to render positive the effecting of continuous multiple contacts, metal to metal, as between the frame and sash members.

In carrying out our invention, in connection with a window constructed according to the above identified patent, we may drill two or more holes through the outer web portions of the stiles of slidable sashes, preferably opposite the above mentioned grooves and in or from these holes we may place, suspend or hang a number of resilient elements, each preferably having an elongated body with a portion thereof bearing against the outer sash guide members of the frame or against the bottom of the groove above described.

Other portions of the elongated bodies of the resilient members may bear inwardly against the perforated outer webs of each sash stile to force said sashes inwardly against the opposite sides of the central guide member or parting strip of the window to prevent rattling of the parts and to seal the joints against air and dust.

The elongated resilient elements above described hence are carried by and slide with the sashes of the window and preferably travel in the above mentioned grooves.

The resilient elements above mentioned may comprise lengths of heavy spring wire

shanks, pre-curved longitudinally and having a right angular hook extension to engage the holes in the window sashes, the said curvature of the shanks being in a direction opposite to the direction of the said right angular extension so that when applied in operative position the spring thrusts exerted by the shank portion will be in the axial line of the said hook extension.

This spring also is so formed that normally it is only slightly flexed in its position between the frame and sash member thus avoiding resistance to the free sliding of the sashes, but is sufficiently strong to prevent lateral sash movement under wind pressure.

In the drawings forming part of this specification similar reference characters are employed to designate corresponding parts throughout the several views, in which:

Fig. 1 is a face view of a window with the elements of our invention applied thereto and partly broken away to show more clearly how one element is suspended or supported in position.

Fig. 2 is an enlarged vertical cross-section of the window on the broken line 2-2 of Fig. 1.

Fig. 3 is a horizontal cross section of one side of the window on a still larger scale taken about on the skip broken lines 3-3 of Fig. 2.

Fig. 4 is a perspective detail view of a preferred form of the resilient element employed.

Referring to the drawings in detail we show at 10 a window of a well known construction having the usual frame 11, sashes 12, comprising meeting rails 13, and upper and lower rails 14 and 15 and stiles or side rails 16. At each side the frame 11 is shaped to form an outer guide wall 17 having a groove 18 formed in its inner face. Carried centrally of the frame 11 is a hollow parting strip 19 and arranged near the inner edge of the frame 11 is another guide strip 20 having a groove 21 in its inner face.

The outer walls of webs 22 of the sash stiles or side rails 16, are provided with appropriately positioned holes 23, through

which hook extensions 24 of wire shanks 25 extend. These wire shanks or lengths are of spring material and are pre-curved outwardly, longitudinally and away from or 5 opposite the rectangularly bent hook extensions 24, as at 26, thus constituting in effect resilient members or elements, which when hung or suspended from the various holes 23, as indicated in Figs. 1 and 2 of the 10 drawings have intermediate spring contact with the bottom of grooves 18 and 21 and at each of their ends with the outer faces of the outer walls or webs 22 of the stiles 16 thus forcing the inner walls of said 15 stiles into intimate air and dustproof contact with the opposite sides of the parting strip 19 to prevent lateral rattling movement of the said sash stiles.

It will be obvious that the resilient anti-rattling members are carried by and slide with the sashes when moved up and down in the window frame and are quickly removed and replaced when necessary.

The action of our spring elements will 20 also press the meeting rails to one another as well as the upper and lower rails to the parting strip, thereby making a perfect closing for the sashes around their total circumferences when the window is closed.

30 The resilient elements may naturally be carried by the stationary portions of the window construction and ride on and exert their action against the sliding sashes, in both forms their action being continuous and 35 permanent, securing an improved closure and rattle proof operation of the sashes in any position thereof.

It is understood that certain changes and 40 variations may be made in the constructions of the various parts of our invention and we reserve our rights to such changes as are within the spirit of the invention and the scope of the appended claims.

45 It is also especially remarked that the anti-rattling device in its preferred embodiment is entirely concealed between the sash and jamb parts of the window.

What we claim as new, is:

1. In a window embodying a frame having inner and outer guides and parting strips between which the stiles of the window sashes are operated, resilient elements comprising rods having their ends bent at an angle to the shank and arranged between the outer faces of the said stiles and said inner and outer guides of the frame, for the purpose set forth.

2. In a window embodying a frame having inner and outer guide and parting strips between which the stiles of the window sashes are operated, resilient elements arranged between the outer faces of the said stiles and said inner and outer guides of the frame, for the purpose set forth, said resilient elements comprising rods carried by

and slidable with the said sashes and having their ends bent at an angle to pass through openings in said stiles.

3. In a window embodying a frame having inner and outer guide and parting strips between which the stiles of the window sashes are operated, resilient elements arranged between the outer faces of the said stiles and said inner and outer guides of the frame, for the purpose set forth said resilient elements being carried by and slid 70 able with the said sashes, and comprising longitudinally extending curved wires having hooks to enter holes in the sides of said sashes.

4. In a window, having a slidable sash with a guide for the same, a resilient element interposed between a stile of the sash and the face of the guide for said element to urge 80 said sash away from said guide, said resilient element being loosely suspended from said sash and adapted to permit the sliding of the sash and acting thereon in any of its positions.

5. In a window, having a slidable sash with a guide for the same, a resilient element interposed between a stile of the sash and the face of the guide for said element to urge 90 said sash away from said guide, said resilient element being in the form of an elongated spring device loosely mounted on the sash and riding on said guide.

6. In a window construction a sash, a frame having guides for said sash and a resilient element loosely suspended at one 100 end from said sash and fitted between the same and one of said guides.

7. In a window construction a sash having an opening therein, a frame having guides for said sash, and a resilient rod having its end bent at an angle adapted to extend through said opening, said rod being fitted between said sash and one of said guides.

8. In a window construction a sash having a stile with an opening therein, a frame having guides for said sash, and means carried by said sash and extending through said opening for holding the sash against one of said guides.

9. In a window construction a sash having a stile with an opening therein, a frame having guides for said sash, and means extending through said opening cooperating between one of said guides and said stile 120 to hold the sash against another of said guides.

Signed at Long Island City, in the county of Queens, and State of New York, this 13th day of May, 1929.

JOHN POLACHEK.
JULIUS A. JEPSEN.
EDMUND PEREMI.
